UNITED STATES PATENT OFFICE.

CHARLES C. MOORMAN, OF DUCOR, CALIFORNIA.

PUMP.

Application filed May 31, 1921. Serial No. 473,676.

To all whom it may concern:

Be it known that I, CHARLES C. MOORMAN, a citizen of the United States, residing at Ducor, in the county of Tulare and State of California, have invented new and useful Improvements in Pumps, of which the following is a specification.

My invention relates to deep well pumps and has for its primary object to provide a most efficient and practical apparatus for pumping oil or water from deep wells with the utmost economy in operating and upkeep expense.

Another object of my invention is to produce a pump of the character described which may be manufactured at a comparatively modest cost and with the parts thereof readily replaced should occasion demand.

A further object of my invention is to utilize the advantages of a double acting, lifting construction which may be operated from a common power source without using double the driving energy required in a single acting construction.

Other objects and advantages will be apparent during the course of the following description.

In the accompanying drawings forming a part of this specification, and in which like numerals are employed to designate like parts throughout the same,

Figure 1 is a view in side elevation of my improved apparatus,

Figure 2 is an end elevation,

Figure 3 is a vertical section on the line 3—4 of Figure 2,

Figure 4 is a similar section but showing an advanced stage in the cycle of operation,

Figure 5 is a horizontal section on the line 5—5 of Figure 1.

In the drawings wherein for the purpose of illustration is shown a preferred embodiment of my invention, the numerals 1 and 2 indicate a pair of pump rods each connected to respective yoked racks 3 and 4 by the pivoted connections 5 and 6 through the links 7 and 8.

These racks are confined upon a drive shaft 9 with freedom of an opposite and vertical driving reciprocal movement between guide plates 10 and 11. The shaft 9 is supported in journal bearings 12 and 13 which in turn are mounted upon the standards 14 and 15, the supporting feet 16 and 17 of which being anchored to a divided foundation 18 by the anchor rods 19 and 20.

The confronting inner faces of the standards are made to receive the ends of the bracing pins 21 and 22 to stabilize the guide plates 10 and 11.

Mounted co-axially upon the shaft 9 is a driving pinion 23 the same being housed within the yokes 3 and 4 and maintained in mesh with the continuous teeth 24 of both yokes.

The yokes are arranged parallel to one another and further include outriggers each having continuous guide channels 25 formed on their respective sides these channels face the guide plates. These channels correspond to the general contour of the toothed inner edges of the yokes and the two adjacent channels of the two yokes are each contacted by guide roller 26 mounted in the adjacent standard (see Fig. 5). The position of the rollers in the channels corresponds to the position of the driving pinion in the yokes the reason for which is obvious.

Mounted on the extended end of the shaft 9 is a drive pulley 27 which may be driven by a belt from a suitable power plant. The primary parts of the apparatus are bolted or otherwise fixed together so that the same may be easily assembled or disassembled when occasion arises.

By driving the pulley 27 a drive will be transmitted to the pinion 23 which in turn will vertically reciprocate the yokes 3 and 4 in opposite directions thus imparting a double acting drive to the pump rods 1 and 2. The yokes in their reciprocation will be properly guided by the rollers 26 in the outrigger channels 25 which will keep the yokes in proper alinement at all stages in the cycles of operation and relieve any tendency of the same to bind or otherwise retard the drive.

It is to be understood that the form of my invention herewith shown and described is to be taken as a preferred example of the same, and that various changes in the shape, size and arrangement of parts may be resorted to without departing from the spirit of the invention or the scope of the subjoined claim.

Having thus described my invention I claim:

In an apparatus of the class described a horizontal drive shaft, a pinion on said shaft rotatable in one direction only, a pair of double acting parallel yokes each having a continuous rack in mesh with said pinion with

2
 the yokes adapted to be driven in opposite vertical directions thereby, complimentary guides on said yokes and a pump rod carried by each yoke and adapted to be alternately lifted by the reciprocation of the yokes, said complimentary guides for the yokes comprising outriggers, channels on the sides of said yokes, guide plates on the sides of said yokes and outriggers and rollers mounted on said guide plates, the rollers on one guide plate being in axial alignment with the rollers on the other of said guide plates, said rollers extending into the channel abutting said guide plates at the point where said rollers are mounted, said shaft being supported in journaled bearings which in turn are supported by divided standards and with the yoke adapted to reciprocate between said standards.

In testimony whereof I affix my signature,

CHARLES CHAVEZ

CHAVEZ

50. I certify that the above is a true copy of the original instrument.
